Primary Examiner — Kelley Donnelly*(74) Attorney, Agent, or Firm* — Michael C. Pophal(57) **CLAIM**

We claim the ornamental design for a merchandiser rack, as shown and described.

DESCRIPTION

FIG. 1 is a perspective view of a merchandiser rack in a closed position, showing our new design;

FIG. 2 is a front view thereof;

FIG. 3 is a rear view thereof;

FIG. 4 is a right side view, and with the left side view being a mirror image thereof;

FIG. 5 is a top view thereof;

FIG. 6 is a bottom view thereof;

FIG. 7 is a perspective view of the merchandiser rack in an open position, showing our new design;

FIG. 8 is a front view thereof;

FIG. 9 is a rear view thereof;

FIG. 10 is a right side view thereof;

FIG. 11 is a left side view thereof;

FIG. 12 is a top view thereof; and,

FIG. 13 is a bottom view thereof.

The broken lines are for the purpose of illustrating the environment of the design only and form no part of the claimed design.
